H. H. Dyke

UNITED STATES PATENT OFFICE.

FRANK BERDOLT, OF COXSACKIE, NEW YORK.

SHIPPING CONTAINER.

Application filed February 21, 1922. Serial No. 538,237.

To all whom it may concern:

Be it known that I, FRANK BERDOLT, a citizen of the United States, and a resident of Coxsackie, county of Greene, and State of New York, have invented a new and useful Improvement in Shipping Containers, of which the following is a specification.

This invention relates to containers and more particularly to shipping cases adapted 10 for use in the transportation of perishable goods at a predetermined temperature.

An important feature of the invention relates to the provision of a container for ice and salt or a brine solution in combination 15 with a compartment containing a porous material adapted to absorb moisture coming from the melting ice, thus keeping the food compartment substantially dry.

Another feature relates to the provision 20 of interconnecting passages between the ice and absorbent material compartments, at the lower portion thereof, thus effectually draining the ice compartment, and reducing the melting rate of the ice.

Another feature relates to the provision 25 of an air pocket or other liquid separating partition between the ice compartment and absorbent material.

Another feature relates to the provision 30 of means for shipping material, such as fish and the like, with the ice packed in directly with the material, with a separate compartment for absorbent material for keeping the ice and material frozen therewith clean and 35 dry.

Another feature relates to provision of a single container for ice and food material, arranged for the insertion therein of a plurality of containers for absorbent material. 40 According to this feature, the absorbent material may be renewed as is found necessary, in relatively small amounts, without material disturbance to the main portion of the device.

Other objects will appear from the following description taken in connection with the accompanying drawings in which Fig. 1 shows a horizontal section taken on the line 1-1, of Fig. 2. Fig. 2 shows a vertical section of one embodiment of the invention. Fig. 3 is a perspective view with parts broken away, and Fig. 4 is a transverse section of a modified embodiment of the invention.

Fig. 5 is a plan view of a further 55 modification of the invention. Fig. 6 is a perspective view with parts broken away,

and Fig. 7 is a transverse section of the absorbent material containers of Fig. 5. Fig. 8 is a plan view of another modification of the invention.

Referring to Figs. 1 and 2, there is shown a shipping container comprising a plurality of nested receptacles, an inner receptacle 10 being arranged to contain material to be preserved during transportation, such as 60 food material, ice cream and the like. Surrounding the inner container 10 and spaced apart therefrom is a second receptacle 11 having its bottom edge portions perforated as by apertures 12. The space between the 65 receptacle 11 and the outer wall of the receptacle 10 is filled with ice for maintaining the temperature of the contents of the inner receptacle 10 substantially constant. Surrounding the second receptacle 11 and 70 spaced therefrom is a third receptacle 13 having its bottom edge portions perforated as by apertures 14. The space 75 between the second receptacle 11 and the third receptacle 13 forms an air pocket. Surrounding the third receptacle 13 and spaced therefrom is an outer receptacle 16, which may 80 rest against and be reinforced by the outer wall 17 of the structure. A single bottom 85 forms the bottom wall of the entire structure and similarly a lid 19 is provided for covering the entire structure. In the embodiment shown in Figs. 1 and 2 the inset receptacles are preferably circular and thus the outer wall 17, the bottom 18 and 90 the lid 19 form a tub shaped container. Suitable handles, such as 20, facilitate handling the tub.

The space between the receptacle 13 and the outermost receptacle 16 is filled with 95 liquid absorbent material, such as sponge, sawdust or the like. The thickness of the absorbent layer should be approximately equivalent to the thickness of the layer of ice between the outer wall of the receptacle 10 and the second receptacle 11. The absorbent material may be held in a wire basket inside of the receptacle 16, so that it may be readily removed for drying.

For separating the absorbent material 105 from the ice, and for preventing ice from clogging the air chamber 15, there is provided a cover 30 tightly fitted upon the receptacles 11, 13 and 16.

In the operation of the structure shown in 110 Figs. 1 and 2 the material to be transported is placed within the receptacle 10 and this

receptacle is then positioned substantially centrally within the tub. The space within the second receptacle 11 as well as the space over the annular cover plate 30 is then filled 5 with a suitable refrigerant, such as ice, and salt or brine solution. As the ice melts the moisture therefrom goes through the apertures 12 and 14 and is absorbed by the absorbent material. This moisture is drawn 10 upon only from the bottom portion and permeates the inner mass of absorbent material by capillary action. The air chamber 15 forms a partition between the absorbent material compartment and the ice compartment 15 for effectually preventing moisture from leaking through to the ice compartment.

In the modified embodiment of the invention shown in Figs. 3 and 4, which is particularly adapted for the shipment and preservation of foods such as fish which may be mixed with the ice or refrigerant material, there is provided an inner receptacle 40 having the bottom edge portions of its walls provided with apertures, such as 41. Surrounding the inner receptacle 40 and spaced therefrom is a second receptacle 42 also having the bottom edge portions of its walls perforated by apertures, such as 43. An air space 44 between the receptacles 40 and 42 30 forms an air compartment. The outer receptacle 45 surrounding the second receptacle 42 and spaced away therefrom forms the outer wall of the structure and between this receptacle and the outer wall of the second receptacle 42 there is provided a mass 35 of absorbent material 46. A bottom plate 47 is provided for all of the receptacles in common and a removable lid 48 serves as a closure for the inner receptacle 40. An annular cover plate 49 is provided for sealing the upper ends of the air compartment 44 and the liquid absorbing material compartment 46. A plurality of separator strips 50 may be provided for reinforcing the side 40 walls of the various receptacles.

In the operation of the structure of Figs. 3 and 4, the food material to be preserved is mixed with a refrigerant, such as ice, and is placed within the receptacle 40. As the ice 50 melts, the moisture therefrom flows through the apertures 41 and 43 and is absorbed by the absorbent material in the compartment 46, thus keeping the food compartment clean and dry.

55 In the modified embodiment shown in Figs. 5, 6 and 7, there is provided an outer casing 60 and a plurality of relatively smaller containers 61 positioned therein. Each of the smaller containers 61 includes a compartment 62 filled with a mass of liquid absorbent material, such as sponge, sawdust and the like, and includes an adjacent air compartment 63. A partition 64 separating these compartments is provided along its 60 lower edge with a plurality of connecting

passages, such as 65. The individual containers 61 are positioned within the casing 60, so that the air space 63 is adjacent to the inner or food space 66, and the wall 67 of the container 61 which faces the space 66 is 70 provided with a plurality of apertures 68. The top of each container 61 is sealed by a suitable cover plate 69 (see Fig. 7).

In the operation of the structure shown in Figs. 5, 6 and 7, the smaller containers 61 75 are positioned within the casing 60 in the manner indicated in Fig. 5. The space 66 may then be filled with food and ice or other material to be shipped and a suitable cover (not shown) may be placed over the casing 80 60. As the ice in the space 66 melts, the moisture therefrom flows through the connecting passage formed by the apertures 65 and 68 and is absorbed by the liquid absorbing material in the compartment 62, thus 85 keeping the food compartment clean and dry. The individual containers 61 may be taken out separately and dried or refilled with fresh absorbent material without disturbing the material in the food compartment. 90

The modified embodiment shown in Fig. 8 is similar to that shown in Fig. 5, excepting that a round tub 80 is employed, the individual containers 61 being positioned 95 along the inner wall thereof. These individual containers may be removed and replaced individually, whenever it is desired to renew the absorbent material.

The invention may be practiced in a variety of ways; for example, the absorbent material may be positioned in the bottom of the container for absorbing the moisture from the ice compartment.

Thus I have provided a shipping container adapted to retain a predetermined temperature for a long time. The ice compartment is effectually kept free of moisture in liquid form, that is, in a form at a temperature above the freezing point, and thus the ice is not subjected to the melting action which would be caused if held in contact with such liquid. This will keep the box cold and the ice will not melt rapidly. Considerable saving in ice is thus effected and a shipping container embodying the features of the invention may be shipped a considerable distance without losing its predetermined temperature.

Illustrative apparatus has been described 120 for the purpose of showing a way in which the invention may be practiced, but it is expressly understood that the scope of the invention is not to be limited thereby, reference being had to the appended claims for that purpose.

I claim:

1. A shipping container comprising a plurality of nested receptacles, one of the spaces formed thereby being arranged to contain a 130

moisture exuding material, and another to contain a moisture absorbing material, the walls of the receptacles between said spaces being provided with connecting passages for 5 moisture.

2. A shipping container having a space for a refrigerant, and a separate space for a liquid absorbing material, said spaces being separated by partitions having apertures 10 for the passage of moisture melted from the refrigerant to the absorbing material.

3. A shipping container having a mass of refrigerant, and a mass of absorbent material spaced apart therefrom by a plurality 15 of separating partitions, said partitions having apertures in their lower edge portions for the passage of moisture melted from the refrigerant to the absorbent material.

4. A shipping container having a mass 20 of cracked ice, and a mass of sawdust spaced apart from the ice by a series of separating partitions, said partitions each having a plurality of apertures in their lower edge portions for conducting moisture melted 25 from the ice to the sawdust.

5. A shipping container for perishable foods, comprising a plurality of nested receptacles forming a series of spaces, a refrigerant in one of said spaces for preserving the food during shipment, a mass of absorbent material in another space, the receptacles having conducting passages between the refrigerant space and the absorbent material space for conducting liquid to 35 keep the refrigerant dry.

6. A shipping container for perishable foods, comprising a plurality of nested receptacles forming a series of spaces, a mass 40 of cracked ice in one of said spaces for preserving the food during shipment, a mass of sawdust in another space, the receptacles having conducting passages between the ice

space and the sawdust space for conducting liquid to keep the ice dry.

7. A shipping container comprising a plurality of nested receptacles, the inner one for material to be preserved, the space outside of the inner receptacle and between it and the next outer receptacle for ice for cooling the contents of the first named receptacle, 45 the space between the second named receptacle and the next outer receptacle for air and adapted to serve as a liquid separating partition, the space between the third named receptacle and the next outer receptacle for 50 liquid absorbing material, the second and third named receptacles having perforations near their bottom extremities respectively for conducting liquid melted from the ice to the liquid absorbing material. 55

8. A shipping container comprising a plurality of nested receptacles, the inner one for ice and the material to be preserved, the space between the inner receptacle and the next outer receptacle for air and adapted to 60 serve as a liquid separating partition, the space between the second named receptacle and the next outer receptacle for liquid absorbing material, the first and second receptacles having perforations near their 65 bottom extremities respectively for conducting material from the ice to the liquid absorbing material. 70

9. A shipping container comprising a receptacle, a mass of absorbent material positioned in one portion thereof, and a mass of ice positioned in another portion for cooling the contents of the container, the absorbent material being arranged to absorb moisture from the ice. 75

In testimony whereof, I have signed my name hereto.

FRANK BERDOLT.
